Atty.

UNITED STATES PATENT OFFICE.

HENRY EARLE, OF WARREN, MASSACHUSETTS.

SPARK PLUG.

Application filed July 19, 1920. Serial No. 397,231.

To all whom it may concern:

Be it known that I, HENRY EARLE, a citizen of the United States, residing at Warren, in the county of Worcester and State of Massachusetts, have invented certain new and useful Improvements in Spark Plugs, of which the following is a specification.

My invention relates to spark plugs such as are used in gas engines for ignition of the explosive mixture.

These spark plugs frequently become covered with carbon and the accumulation of carbon between the two electrodes frequently results in short circuits which greatly reduce the efficiency of the spark plug.

The object of my invention is to insulate, as completely as possible, the surface of the central electrode or other metallic parts of a spark plug, so that no current or ignition spark can pass except between two small unprotected spots. I have found it sufficient for the purpose to coat the central electrode of a spark plug with a difficultly reducible, metallic oxide, preferably of the iron and chromium groups of metals. For instance, the surface of the central wire electrode of a spark plug is coated with an oxide of uranium that is not reducible in the gases formed in an internal combustion engine, and is for all practical purposes non-conducting. Also, I have found that if a metallic surface is coated with a metallic phosphate or phosphide, it is rendered practically nonconducting. For this purpose, I dip the metal to be coated in a solution of phosphoric acid and then apply heat, heating it to a cherry red.

The phosphate first formed on the surface is converted by the high temperature into a metaphosphate and at a still higher temperature into a phosphide which is highly non-conducting. After a spark plug electrode is completely coated, I remove the coating with a sharp instrument to form an uninsulated spot just opposite the discharge point of the other electrode, so that no current can pass except where the spot is formed and the coating is removed. The rest of the spark plug being completely insulated, there can be no leakage of current by a coating of carbon or soot forming on the inside of the plug or on the electrode. The spark, being confined to a very small surface, is intensely hot, much more so than if the unprotected surface was larger and there being no leakage of current through

an accumulation of carbon or soot, the full strength of the current is utilized.

Although the voltage on these spark plugs is high the thin non-conducting coating is sufficient to resist the penetration by any charges which might pass in a short circuit since the electricity will always pass over the line of least resistance or through the uninsulated spot.

It is evident that the non-conducting coating may be an adherent coating as shown or it may be a thin covering of insulating material not formed as an adherent coating.

I have illustrated my invention by means of the accompanying drawing in which is shown the two electrodes of a spark plug.

Referring to the drawing:

1 shows the main or central wire electrode of a spark plug and 2 is the terminal wire of the annular electrode 3, the spark being formed between the end of the wire 2 and the side of the wire 1.

The insulating coating of metallic oxide or other insulating material is applied to the surface of the electrode wire 1 by dipping the wire one or more times into a solution and then heating the wire to a low red heat.

A spot 4 is then scraped by a suitable tool from the side of the wire 1 directly opposite to the end of the wire 2 or at the point where the spark jumps across.

The entire effective length of the wire 1 is effectively insulated except the one small spot so that there is no chance of any short circuit being formed.

A spark plug made on this principal costs but a trifle more than the ordinary spark plug and absolutely prevents short circuiting by the carbon formed within the combustion chamber, a source of much trouble in the present gas engine practice.

I do not claim for my non-conducting coating that it will insulate against a high tension intermittent current but only against a direct current.

It is evident that where the tension on the coating becomes sufficient to perforate the same the coating will be punctured at some spot by the spark and the subsequent effect will be the same as if I formed the spot in manufacturing the electrode. As high tension alternating currents are mostly used on gas engines, there is no real necessity of scraping off the coating to form the base spot.

• I claim:—

1. A spark plug having two electrodes, one of the said electrodes having an adherent coating of non-conducting material extending over substantially all its effective surface, a portion of said non-conducting material being removed from a spot opposite the other electrode.
2. A spark plug having two electrodes, one of said electrodes being coated with a coating of metallic phosphate, the said coating being removed from a spot opposite the other electrode.
3. A spark plug having two electrodes,

one of said electrodes having been dipped in a solution of phosphoric acid and subsequently heated to form a non-conducting coating, said coating being removed from a spot opposite the other electrode. 15

4. A spark plug having two electrodes, one of said electrodes having a coating of metallic phosphate overlaid with a coating of uranium oxide, a portion of said double coating being removed at a spot opposite the other electrode. 20

25 In testimony whereof I affix my signature.

HENRY EARLE.
